UNITED STATES PATENT OFFICE.

BENJAMIN V. GINTZ, OF AKRON, OHIO.

HOT-AIR DEFLECTOR.

SPECIFICATION forming part of Letters Patent No. 557,068, dated March 24, 1896.

Application filed November 20, 1895. Serial No. 569,527. (No model.)

To all whom it may concern:

Be it known that I, BENJAMIN V. GINTZ, a citizen of the United States, residing at Akron, in the county of Summit and State of Ohio, have invented a certain new and useful Improvement in Hot-Air Deflectors, of which the following is a specification.

My invention has relation to the construction of deflectors for hot air arising from registers, radiators, &c.

The objects of my invention are to produce a deflector which shall effectually turn the air out into the middle portion of a room, and one containing a tank of warm water to keep the air humid, and one to catch the dust; also to so suspend this tank that it can readily be reached for cleaning.

To the aforesaid objects my invention consists in the peculiar and novel construction, combination and arrangement of the various parts hereinafter described, and then specifically pointed out in the claims, reference being had to the accompanying drawings, forming a part of this specification.

In the accompanying drawings, in which similar reference - numerals indicate like parts, Figure 1 is a perspective view of a complete deflector; Fig. 2, a view of one form of deflector with the near end plate removed; Fig. 3, a similar view showing a different manner of hinging the tank; Fig. 4, a view of the tank itself; Fig. 5, a side elevation of the spout by which the tank is filled.

In the drawings, 1 and 2 are the end plates, which are united to a top plate 3, which is substantially in an involute-curve shape, covering nearly all one side, the top and above one-third of the other side, between the ends 1 and 2, and terminating in a sharp inturned curve, leaving an open space between it and the bottom. A strap 4 extends between the plates 1 and 2 for strength only.

The top plate, 3, does not extend quite to the base of the deflector, but leaves a narrow space extending across the entire distance between the plates 1 and 2. Beneath this plate 3 and separated a little space from it, but substantially concentric therewith, is a shield 5, extending between plates 1 and 2 and from the base of the deflector to a point substantially level with the sharp curve of plate 3.

Hinged in the upper part of plates 1 and 2

is what I call a "tank" 6, which consists of a pair of troughs 7 and 8, parallel to each other, and held thus by a strap 9 and by two end plates 10, which also form the ends of the troughs 7 and 8. The edge of trough 8, or 7, as the case may be, is rolled into a small tube 11, through which passes a large wire serving as a journal on which the troughs 60 are hinged. It is long enough to enter the side plates, 1 and 2.

The troughs are tilted toward one another or the reverse, or in the same direction, as the requirements of the case direct, in order 65 to retain the water when tipped down for cleaning. On one of these troughs is a small catch 12 to hold the trough in place and fastens into a small slot (not necessary to show) in the top plate, 3, when the troughs are 70 hinged as shown in Fig. 3, and this catch 12 engages a lug 13 when the troughs are hinged as shown in Fig. 2.

On the outside of plate 2 is a pocket 14, terminating in a short tube 15, with its free end 75 directly over the trough to contain the water, so that water may be placed in the trough from outside the deflector.

In operation in each case one trough is filled with water and the deflector placed over 80 a register. The hot air arising (indicated by the arrows) from the register passes along the concave surface of the shield 5. There it is joined by cold air drawn up by the current of hot air from the register through the space 85 between the plate 3 and shield 5. The mixture of hot and cold air passes around the concave surface, down over trough 7, and out between the troughs 7 and 8 and the open side. In passing over trough 7 the dust particles 90 will be precipitated into it, there to remain until removed.

The trough 8 of water, being warmed by the hot air, evaporates and serves to keep the air moist and agreeable.

The object in admitting the air of the room through the air-duct between plate 3 and shell 5 is twofold, to wit: As the air along the floor of the room is being drawn constantly through the duct, it is warmed, and thus prevents a 100 large body of cold air accumulating around the deflector, and, further, were the duct not there only the air arising from the register would be cleansed from the particles of dust,

whereas in this deflector all the air in the room is gradually passed over the surface of the water in the tank.

When it is desired to clean the deflector, 5 the catch 12 is unfastened and the tank swings down within reach without spilling water, because of the tilted position of trough 8.

What I claim is—

1. In a deflector for hot air, the combination with two side plates and a curved top, of a tank hinged between said side plates and under said top, and a catch arranged to retain said tank in position when desired, substantially as shown and described.

15 2. The combination in a hot-air deflector having two side plates and a rolled top, of a double tank, hinged to said side plates and under said top, one of said tanks adapted to contain water when in use, and a catch 20 adapted to retain said tank in place, substantially as shown and described.

3. The combination in a deflector of the 25 class designated, of a pair of side plates, a curved top reaching on one side nearly to the base of the deflector, a shield within said top

extending from the base of said deflector to a point nearly to the top thereof, and separated therefrom a little distance, a double tank hinged between said side plates and adapted, when desired, to be swung down on 30 said hinges, substantially as shown and described.

4. In a hot-air deflector of the class designated, having two side plates and a curved top extending on one side nearly to the base 35 of the deflector, a shield concentric therewith and separated therefrom a little distance, and extending from the base of the deflector a portion of its height, a double tank hinged in the concave portion of said tank and a 40 pocket and inlet-pipe placed in one of said plates, and directly over one of said tanks, substantially as shown and described.

In testimony that I claim the above I hereunto set my hand.

BENJAMIN V. GINTZ.
